UNITED STATES PATENT OFFICE.

LAURA E. CRUVER, OF TACOMA, WASHINGTON, ASSIGNOR OF ONE-HALF TO OSCAR M. GLASS, OF TACOMA, WASHINGTON.

COMPOSITION FOR THE MANUFACTURE OF LAUNDRY AND TOILET SOAP.

No Drawing.

Application filed October 24, 1921. Serial No. 509,975.

To all whom it may concern:

Be it known that I, LAURA E. CRUVER, a citizen of the State of Washington, residing at 9606 Park Avenue, Tacoma, in the county of Pierce, State of Washington, have invented a new and useful Composition for the Manufacture of Laundry and Toilet Soap, of which the following is a specification.

The object of my invention is the production of a laundry soap suitable for cotton and woolen goods and also for silks and fine fabrics and for general toilet purposes.

My composition consists of a mixture of white soap taken as a body for the preparation, and coal oil, lemon juice, lettuce juice, cucumber juice, borax powder, paraffine, oil of almond, cocoanut oil and bluing.

In preparing the composition I prefer to use the ingredients in about the following proportions:

1 lb. white soap, 2 oz. coal oil, 2 oz. lemon juice, 2 oz. lettuce juice, 2 oz. cucumber juice, 1 tablespoon borax powder, 3 oz. paraffine, 10 drops oil of almond, 2 tablespoons cocoanut oil, 1 oz. bluing.

The ingredients mixed in proportion

named will produce a soap which will remove dirt from cotton and woolen goods without rubbing and woolen goods will come clean without shrinking.

For toilet soap the bluing may be omitted and the coal oil is reduced by half.

My composition is light, effective, pleasant to use and free from irritating results upon the skin, and in the whole possesses a high degree of all of the desired properties of a superior toilet and laundry soap.

I claim:

1. A laundry soap consisting of the following: 1 lb. white soap, 2 oz. coal oil, 2 oz. lemon juice, 2 oz. lettuce juice, 2 oz. cucumber juice, 1 tablespoon borax powder, 3 oz. paraffine, 10 drops oil of almond, 2 tablespoons of cocoanut oil, 1 oz. bluing.

2. A toilet soap consisting of the following: 1 lb. white soap, 1 oz. coal oil, 2 oz. lemon juice, 2 oz. lettuce juice, 2 oz. cucumber juice, 1 tablespoon borax powder, 3 oz. paraffine, 10 drops oil of almond, 2 tablespoons cocoanut oil.

LAURA E. CRUVER.
